H. W. WEYMANN

TAIL PIECE FOR STRINGED MUSICAL INSTRUMENTS

Filed Oct. 6, 1922

INVENTOR
Harry W. Weymann
By W. W. Williamson Atty.

UNITED STATES PATENT OFFICE.

HARRY W. WEYMAN, OF PHILADELPHIA, PENNSYLVANIA. ASSIGNOR TO H. A. WEYMAN & SON, INC., OF PHILADELPHIA, PENNSYLVANIA, A CORPORATION OF PENNSYLVANIA.

TAILPIECE FOR STRINGED MUSICAL INSTRUMENTS.

Application filed October 6, 1922. Serial No. 592,709.

My invention relates to new and useful improvements in a tail piece for stringed musical instruments, such as banjos, and has for its object to provide a device of this 5 character for attachment to the body of the musical instrument engaging the strings thereof whereby a greater or less pressure may be brought to bear upon the strings below the bridge.

Another object of the invention is to provide a skeleton body member pivotally attached to a bracket member, the latter provided with means for direct attachment to the body of a musical instrument or to the 15 ordinary metallic bracket on some instruments of this class.

A further object of my invention is to provide for enclosing the pegs or lugs to which the ends of the strings are attached 20 in order to prevent the clothing of the musician from coming in contact with said lugs which would have a tendency to tear the same.

A still further object of the invention is 25 to provide a simple arrangement of elements whereby the cross bar of the body will be forced or moved toward the parchment head of the instrument in order to add a tension to the strings for increasing the tone of the musical instrument.

With these ends in view, this invention 30 consists in the details of construction and combination of elements hereinafter set forth and then specifically designated by

the claim.

In order that those skilled in the art to 35 which this invention appertains, may understand how to make and use the same, I will describe its construction in detail, referring 40 by numerals to the accompanying drawing forming a part of this application, in which:—

Fig. 1, is a conventional side elevation of 45 a banjo showing the application of my improved tail piece.

Fig. 2, is an enlarged plan view of the tail piece with the removable cover partly broken away to illustrate the interior construction.

Fig. 3, is a sectional end view thereof.

Fig. 4, is a section at the line 4—4 of Fig. 2 with the sliding cover removed.

In carrying out my invention as here embodied, 2 represents the body of a stringed musical instrument, such as a banjo, 3 the 55 strings thereof and 4 the bridge on which the strings rest, the said bridge standing upon the parchment head of the musical instrument.

The numeral 5 denotes my improved tail 60 piece comprising a bracket member 6 having a hole 7 through the upright portion 8 thereof whereby said bracket member may be attached by suitable securing means directly to the body 2 of a musical instrument, said 65 bracket member also having a foot 9 in which is formed a hole 10 for the passage of suitable securing means such as a screw for attachment to a metallic bracket when such a bracket is carried by the body of this 70 class of musical instruments. At the upper end of the upright portion 8 of the bracket member is an inturned panel 11 having an ear 12 at each end and carrying a plurality of undercut pegs or lugs 13 for registration 75 with the loops of the different strings on the musical instrument.

To the ears of the bracket member is pivoted the skeleton body 14 by means of rivets 15 or their equivalent passing through 80 the ears 12 and the arms 16 of the skeleton body. Connected with the inner ends of the arms 16 is a cross bar 17 adapted to overlie and engage the musical instrument string below the bridge or between said bridge and 85 the tail of the instrument.

At the outer ends of the arms is a downwardly turned portion or hanger 18 into which is threaded a set screw 19 the inner 90 ends of which is adapted to impinge against the outer face of the upright portion 8 of the bracket member so that as said set screw is screwed inward the downwardly turned portion or hanger 18 will be moved outward or away from the bracket member and thereby cause the cross rod 17 to move downward toward the head of the instrument for producing the desired tension upon the strings.

The outer ends of the arms 16 are undercut or beveled, as indicated at 20, for the 100 coaction with the inturned sides 21 of the removable cover 22 which by means of said sides is slidably mounted upon the rear portion of the skeleton body to enclose or cover

the pegs or lugs 13 to prevent contact of the latter with the clothing of the musician. This cover is also provided with a down-turned lip 23 which engages the outer end 5 of the arms of the hanger 18 to limit the inward movement of said cover and also house the upper portion of said hanger.

By constructing a tail piece in the manner described it is adapted for attachment to 10 the musical instrument in either of the two ways in which tail pieces are generally secured to a musical instrument thereby overcoming the necessity of reconstructing the musical instrument or adding additional 15 parts. Further the construction of the tail piece is such that the instrument strings may be readily passed beneath the cross bar and quickly attached to the pegs or lugs provided for securing of said strings. 20 It is of considerable advantage to have the attaching pegs or lugs covered or enclosed in order to prevent undue wear upon the clothing of the musician and while this is accomplished by the cover referred to 25 above the latter being removable permits the strings to be readily and easily fastened in place.

Of course I do not wish to be limited to the exact details of construction as herein 20 shown as these may be varied within the limits of the appended claim without departing from the spirit of my invention.

Having thus fully described my invention, what I claim as new and useful is:—

A tail piece for a stringed musical instrument comprising an angle shaped bracket, means on the vertical part thereof for permitting it to be fastened to an instrument, the horizontal part of the bracket being flat with an ear at each side thereof, hook-shaped 35 projections on said flat part for receiving the looped ends of the strings of the instrument, a skeleton frame including side members and front and rear cross pieces and having its side members pivoted to the ears, 40 with its front cross piece engaging the strings, a depending piece on the rear cross piece, a set screw carried by the depending piece and engaging the vertical part of the bracket for adjusting the pressure of the 45 front cross piece of the frame on the strings, the side pieces adjacent the rear cross piece of the frame having their outer edges tapering downwardly and inwardly and a cover 50 having side flanges thereon extending downwardly and inwardly for engaging the said edges so that the cover is slidably mounted on the frame and covers the projections and a flange on the rear of the cover engaging 55 the depending piece.

In testimony whereof, I have hereunto affixed my signature.

HARRY W. WEYMAN.
